UNITED STATES PATENT OFFICE

134,314

DESIGN FOR A RECORDING TELEGRAPH CABINET

Walter J. Zenner, Des Plaines, Ill., assignor to Teletype Corporation, Chicago, Ill., a corporation of Delaware

Application June 18, 1941, Serial No. 101,529

Term of patent 14 years

To all whom it may concern:

Be it known that I, Walter J. Zenner, a citizen of the United States, residing at Des Plaines, in the county of Cook and State of Illinois, have invented a new, original, and ornamental Design for a Recording Telegraph Cabinet, of which the following is a specification, reference being had to the accompanying drawings, forming a part thereof.

Fig. 1 is a perspective view of a recording telegraph cabinet displaying the front and left sides showing my new design; and

Fig. 2 is a side elevational view of a recording telegraph cabinet viewing the unit from the right side.

I claim:

The ornamental design for a recording telegraph cabinet, substantially as shown.
